ELECTRICAL CONNECTOR

Melvin Korman, North Attleboro, Mass., and Luther M. Sheldon, Cranston, R.I., assignors to General Electric Co., New York, N.Y.

Filed Apr. 18, 1974, Ser. No. 462,067

Term of patent 14 years

Int. Cl. D13—03
U.S. Cl. D26—1 B

FIG. 1

FIG. 2

FIG. 3

FIG. 4

FIG. 5

FIG. 6

FIG. 7

FIG. 8

FIG. 9

FIG.10

FIG.11

FIG.12

FIG.13

FIG.14

FIG. 15

FIG. 16

FIG. 1 is a front elevational view of an electrical connector showing our new design, the connector being female;

FIG. 2 is a side elevational view thereof;

FIG. 3 is a back elevational view thereof;

FIG. 4 is a bottom plan view of one end thereof;

FIG. 5 is a top plan view of the opposite end thereof;

FIG. 6 is an enlarged view of the ribbing on the upper and lower parts of the connector;

FIG. 7 is a side elevational view of another embodiment of the female connector of our design;

FIG. 8 is a top plan view of the connector of FIG. 7;

FIG. 9 is a side elevational view of another embodiment of our design, the connector being male;

FIG. 10 is a perspective view of another embodiment of the female connector of our design;

FIG. 11 is a top plan view of the connector of FIG. 10;

FIG. 12 is an elevational view of the article illustrated in perspective view in FIG. 10;

FIG. 13 is a side elevational view of another embodiment of the female connector of our design;

FIG. 14 is a top plan view of the connector of FIG. 13;

FIG. 15 is a top plan view of a connector as illustrated in FIG. 9;

FIG. 16 is a bottom plan view of a connector as illustrated in FIG. 9.

The bottom plan configuration of the connectors of FIGS. 7, 10, 12, and 13 are similar in outline to that of FIG. 4.

We claim:

The ornamental design for an electrical connector, as shown and described.
